(57) **CLAIM**

The ornamental design for a dispenser tip for a foam dispenser, as shown and described.

DESCRIPTION

FIG. 1 is a top perspective view of a dispenser tip for a foam dispenser showing our new design;

FIG. 2 is a bottom perspective view thereof;

FIG. 3 is a side elevational view thereof, the foam dispenser being shown in broken lines for illustrative purposes only and forming no part of the claimed design;

FIG. 4 is a top plan view thereof; and,

FIG. 5 is a bottom plan view thereof.
